Primary Examiner — Bao-Yen T Nguyen*Assistant Examiner* — Christopher John Suarez La Rosa(74) *Attorney, Agent, or Firm* — Foley & Lardner LLP(57) **CLAIM**

I claim the ornamental design for a multi-tier basket, as shown and described.

DESCRIPTION

FIG. 1 is a front perspective view of a multi-tier basket showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a front side exploded view thereof.

FIG. 7 is a top plan view thereof; and,

FIG. 8 is bottom elevational view thereof.

Present invention relates to design of a 3 tier basket stand which also can be assembled with only two baskets.
